UNITED STATES PATENT OFFICE.

LOUIS STIRN, OF NEWARK, NEW JERSEY, ASSIGNOR TO JOSEPH FISCH, OF NEWARK, NEW JERSEY.

DESIGN FOR A REGULAR UTILITY SERVICE-CAP.

52,590.

Specification for Design.

Patented Oct. 15, 1918.

Application filed April 9, 1918. Serial No. 227,577. Term of patent 7 years.

To all whom it may concern:

Be it known that I, LOUIS STIRN, a citizen of the United States, residing at Newark, in the county of Essex and State of New Jersey, with post-office address at No. 20-24 Arch street, said city, county, and State, have invented a new, original, and ornamental Design for a Regular Utility Service-Cap, of which the following is a specification, reference being had to the accompanying drawing, forming a part thereof.

Figure 1 is a perspective view of a cap, showing my new design.

Copies of this patent may be obtained for five cents each, by addressing the "Commissioner of Patents, Washington, D. C."

Fig. 2 is a similar perspective view of a cap, showing my new design in a slightly different position.

Fig. 3 is a top view of a cap, showing my new design.

I claim:

The ornamental design for a regular utility service cap, as shown.

LOUIS STIRN.
